UNITED STATES PATENT OFFICE.

CHESTER A. FINCH, OF SPOKANE, WASHINGTON.

ADJUSTABLE CURVE.

1,169,245.

Patented Jan. 25, 1916.

Continuation of application Serial No. 821,903, filed March 2, 1914. This application filed May 21, 1914.
Serial No. 840,036.

To all whom it may concern:

Be it known that I, CHESTER A. FINCH, a citizen of the United States, residing at Spokane, in the county of Spokane and State of Washington, have invented certain new and useful Improvements in Adjustable Curves, of which the following is a specification.

This invention relates to improvements in instruments which have come to be known as adjustable curves, and the device of my invention is capable of advantageous utility in any connection and under all conditions in which instruments of this character are serviceable, this application being a continuing application, of my pending application filed March 2, 1914, Serial No. 821,903.

It is one of the features of my invention to provide an adjustable curve instrument with an endless resilient ruler together with means connected with the endless ruler and adjustable by the operator to shape the ruler to the desired curve.

It is a further object of my invention to provide adjusting means for the endless ruler which means may be in the form of bars adapted to be shifted with respect to each other to flex the ruler so as to shape the same to the desired curvature.

A further object is to provide bar actuating means which may include a pointer adapted to center the instrument on a given center with respect to the endless or other curved line to be drawn.

Other features and objects of the invention will be more fully described in connection with the accompanying drawings and will be more particularly pointed out and ascertained in and by the appended claims.

In the drawings:—Figure 1, is a view in plan of an instrument embodying one form of my invention with the endless ruler shaped to draw a true circle. Fig. 2, is a similar view showing the instrument adjusted to shape the endless ruler to an oval formation. Fig. 3, is a similar view illustrating a reverse curvature adjustment. Fig. 4, is a sectional view on line 4—4 of Fig. 3. Fig. 5, is a sectional view on line 5—5 of Fig. 4. Fig. 6, is a sectional view on line 6—6 of Fig. 3. Fig. 7, is a sectional view on line 7—7 of Fig. 3.

Like characters of reference designate

similar parts of the different figures of the drawings.

As illustrated, 1 designates an endless resilient ruler which is adapted to be flexed to shape the same to any desired curve and which may be of any approved material and construction.

Adjusting members which are shown in the form of rack bars 2 and 3, are provided for adjusting the ruler 1 and the rack bars are provided with teeth 4 and 5, as will be clearly seen by reference to Fig. 1. Each rack bar is provided with a feather projecting downwardly from the base thereof and one of such feathers is shown in Fig. 6, for bar 2, as indicated at 6, it being understood that bar 3 is provided with a like feather, as shown in dotted line in Fig. 1.

Centrally of the instrument I provide means for guiding and shifting and also locking the bars 2 and 3, said means being shown more particularly in Fig. 4. As illustrated, said means includes a frame having a base portion 7 which is grooved at 8 and 9 to receive the feathers of the bars 2 and 3. An upper member 10, of the frame, is provided with depending sides 11 and 12 which are adapted to rest upon the base frame member 7, and be fixed thereto by means such as rivets 13 and 14. Centrally of the frame I dispose a pinion 15 for mesh engagement with the rack teeth 4 and 5 so that when the pinion 15 is rotated it will impart shifting movement to the rack bars 2 and 3 is unison and in opposite direction. Means is provided for locking the bars 2 and 3 in adjusted positions and as shown said means may comprise a set screw 16 threaded into end 12 of the upper frame member 10, for engagement with rack bar 3 so to act therethrough and through the pinion 15 to lock both bars in adjusted positions. The pinion 15 is fixed between the upper and lower frame members 7 and 10 on a sleeve spindle 17 which is rotatively mounted in the frame members 7 and 10. A nut 18 is shown threaded on the lower end of the spindle 17 and a finger grip or thumb nut 19 is shown threaded on the upper end of the spindle thereby holding the spindle against longitudinal displacement in the central frame but permitting rotation of the spindle therein. The spindle 17 is bored at 20, and is counter-

bored at 21, to provide a shoulder 22, the purpose of which will presently appear. A centering stem 23 is longitudinally movable in the spindle 17 and is provided at one end 5 with a pointed terminal 24 and at its other end with a removable thumb grip 25. A collar 26 is fixed on the pointer stem and between the collar 26 and the shoulder 22 is interposed a spring 27 to normally hold the pointer stem 23 in the position shown. In order to limit movement of the pointer stem 23, upwardly, I provide a stop which may be in the form of a collar 28 which may be threaded into the spindle 17.

15 By means of the foregoing construction, the pointer stem 23 may be shifted downwardly so as to thrust the pointed terminal 24 into a given or selected center about which the curve is to be drawn so that the stem 23 20 may function as a center spotter.

The adjusting members or bars 2 and 3 are not directly connected with the ruler 1 but are connected therewith through the interposition of guiding blocks which I will 25 now describe in detail. One of said blocks is indicated at 28 and the other at 29. Bar 2 is connected rigidly with block 28 and slidably with block 29 and bar 3 is connected rigidly with block 29 and is slidably connected with block 28. In view of the fact 30 that both blocks are similar in construction only one need be described in detail and reference will be made more particularly to Figs. 6 and 7.

35 The feather on bar 3, as will be seen more particularly by reference to Fig. 1, does not extend to block 29, or to that end of bar 3 which is secured to block 29, and therefore bar 3 is fixed to block 29 by being seated in 40 a suitable recess or mortise in said block, as shown in Fig. 7. A rivet 30 extends through block 29 and bar 3 and through a retaining strip 31 which is disposed transversely of block 29. Bar 3 may be additionally secured 45 by a rivet 32 which is disposed at one side of rivet 30. The retaining strip 31 is additionally anchored by a rivet 33 which extends through block 29 and which secures a locating point element 34 having a pointed terminal 35'. The locating point element 50 34 is likewise seated in a recessed or mortised bottom portion of the block 29. Said retaining strip 31 extends across in overlapping relation with adjusting bar 2 and is 55 further secured to block 29 by a rivet 35. The feather 6 of bar 2 projects into a feather-way 36 of block 29 as will be clearly seen by reference to Fig. 7. It will thus be seen that adjusting rack bar 3 is fixed to block 60 29 and adjusting rack bar 2 is slidably connected with block 29 in such a manner as to hold the parts in predetermined relation with respect to each other but to permit relative movement of adjusting member 2 with 65 respect to adjusting member 3.

Block 29 is secured to the resilient ruler 1 and in order to permit of the adjustment shown in Fig. 2, I converge the outer end of block 29, as indicated at 37. At the apex of said block I provide a screw 38 which extends through an opening in the ruler 1 in such a manner as to connect the latter with the block 29 and also permit of the different adjustments shown. To prevent rupture of the resilient ruler, I may 70 round the inner face of the head 38 so as to permit of the adjustment shown in Fig. 3. Block 28 is provided with a retaining strip 39 which is secured in place by rivets 40 and 41. Rivet 41 serves to hold a locating point 80 element 42 similar to that indicated at 35'. The retaining strip 39 slidably connects bar 3 with block 28 and I rigidly secure block 2 to block 28 by means of a rivet 43 and a rivet 44, the latter serving to secure the retaining strip 39 to block 28. Block 28 is connected with ruler 1 by a screw 45 in a manner similar to the connection of ruler 1 with block 29.

It will be seen by reference to Fig. 4 that the central adjusting frame means is located somewhat above the bottom the spindle 17, thereby disposing the bars 2 and 3 appreciably above the surface of the drawing board. Blocks 28 and 29 likewise serve 95 to correspondingly elevate bars 2 and 3 but the ruler 1, as will be seen more particularly in Fig. 6, is connected with the blocks in such a manner as to lie close to the drawing surface. By this arrangement, I dispose the bars 2 and 3 above the ruler 1 so that the bars can be shifted without interference with the ruler because they overhang the latter.

As illustrated in Fig. 2, the bars 2 and 3 105 may be graduated, as at 46 and 47, so as to provide for a reading abreast of the retaining strips 31 and 39, whereby the instrument may be used as a computator, or to indicate the diameter of the circle of which the curve form is an arc. The graduations 46 and 47 are useful in marking a curve so as to determine the next adjustment of the instrument. Suppose that a curve had been drawn on an adjustment where the block 31 110 registers at numeral 6 on bar 2, or where the block 39 registers with numeral 9 on bar 3, then such curve would be marked 6, or 9, as the case might be, on the drawing. The draftsman could then have a reference for again adjusting the instrument to the same curvature at a subsequent time. This is only one of the many utilities of these graduated portions. In this form of 115 the invention, the central frame and also the end block frames are connected with the bars 2 and 3 in such a manner as to at all times maintain the bars in absolute predetermined relation, which as shown, is a parallel relation with respect to each other. 120 125 130

The function of the locating points 35' and 42, is to indicate the location of the diameter of the circle of which the curve to be drawn is an arc. As an example of one utility of the locating points 35' and 42, it may be stated that intersecting vertical and horizontal lines are generally drawn and the locating points are brought into registry with the horizontal lines so as to properly locate the instrument for drawing the curve desired. In this event, the point 24 would be disposed at the intersection of the vertical and horizontal lines. Of course this is only one of the many utilities of my improved locating points.

It is believed that the advantages and utility of my invention will be clearly understood from the foregoing description and while I have herein shown and described one specific form of my invention, I do not wish to be limited thereto except for such limitations as the claims may import.

I claim:

1. In an adjustable curve instrument of the class described, an endless resilient one-piece ruler, bars connected with said ruler, and means for shifting said bars with respect to each other to cause said ruler to assume the desired curve, substantially as described.

2. In an adjustable curve instrument of the class described, an endless resilient ruler, bars for shifting said ruler to cause the same to assume the desired curve, a guide frame engaging said bars between their ends, means between said bars and mounted in said frame for shifting said bars with respect to each other to shape said structure to the desired curve, and devices slidably connected with said bars on opposite sides of said frame for coaction therewith to hold said bars in predetermined relation with respect to each other, substantially as described.

3. In an adjustable curve instrument of the class described, an endless resilient ruler, blocks pivoted to said ruler, adjusting bars having the alternate ends fixed and slidably connected with said blocks, and means between said blocks for shifting said bars to shape said ruler to the desired curve, substantially as described.

4. In an adjustable curve instrument of the class described, an endless resilient ruler, blocks pivoted to said ruler, adjusting bars each having one end rigidly connected with one block and its other end slidably connected with the other block, and means for shifting said bars to shape said ruler to the desired curve, substantially as described.

5. In an adjustable curve instrument of the class described, an endless resilient ruler, adjusting bars, devices pivoted to said ruler and connected with said bars to hold the latter in parallel relation with respect to each other, and means for shifting said bars to shape said ruler to the desired curve, substantially as described.

latter in parallel relation with respect to each other, and means for shifting said bars to shape said ruler to the desired curve, substantially as described.

6. In an adjustable curve instrument of the class described, an endless resilient ruler, bars, devices pivoted to said ruler and alternately fixedly and slidably connected with said bars to hold the latter in parallel relation with respect to each other, and means for shifting said bars to shape said ruler to the desired curve, substantially as described.

7. In an adjustable curve instrument of the class described, an endless resilient ruler, bars, devices connected with said ruler and with said bars to hold the latter in parallel relation with respect to each other, and means for shifting said bars to shape said ruler to the desired curve, substantially as described.

8. In an adjustable curve instrument of the class described, a resilient ruler, blocks pivoted to said ruler, adjusting bars having their alternate ends fixed and slidably connected with said blocks, and means for shifting said bars to shape said ruler to the desired curve, substantially as described.

9. In an adjustable curve instrument of the class described, a resilient ruler, bars, devices pivoted to said ruler and connected with said bars to hold the latter in parallel relation with respect to each other, and means for shifting said bars to shape said ruler to the desired curve, substantially as described.

10. In an adjustable curve instrument of the class described, a resilient ruler, means connected with said ruler to shape the same to the desired curve, rotative mechanism for operating said means, and centering means movable axially with respect to said rotative mechanism, substantially as described.

11. In an adjustable curve instrument of the class described, a resilient ruler, means connected with said ruler to shape the same to the desired curve, rotative mechanism for operating said means, and spring controlled centering means movable axially with respect to said rotative mechanism, substantially as described.

12. In an adjustable curve instrument of the class described, a resilient ruler, adjusting rack bars for shaping said ruler to the desired curve, a frame engaging said bars, a pinion meshing with said bars, a sleeve spindle rotatable in said frame and fixed to said pinion, and a centering stem movable axially in said spindle, substantially as described.

13. In an adjustable curve instrument of the class described, a resilient ruler, adjusting bars, blocks connected with said ruler and with said bars and provided with locating points, and shifting mechanism for

said bars disposed between said blocks and including centering means, substantially as described.

14. In an adjustable curve instrument of
5 the class described, a resilient ruler, adjusting bars therefor, blocks connected with said ruler and with said bars to support the former adjacent the drawing surface and

the latter above said ruler, substantially as described.

In testimony whereof I affix my signature in presence of two witnesses.

CHESTER A. FINCH.
